Specification of Letters Patent.

Patented Mar. 15, 1921.

Application filed June 5, 1919. Serial No. 301,991.

To all whom it may concern:

Be it known that we, JOHN F. SOLTER and WILLIAM GINDLER, citizens of the United States, residing at Collinsville, in the county 5 of Madison and State of Illinois, have invented certain new and useful Improvements in Ladders, of which the following is a specification.

Our invention relates to improvements in 10 ladders and more particularly to step ladders of the extension type.

The object of our invention is to provide 15 a four piece extension step ladder which can be used as an inverted V-shaped ladder, as an ordinary straight ladder by disassembling same, or as a ladder having two supporting members one of which is shorter than the other to permit one supporting member of 20 the ladder to stand on a higher level than the other supporting member.

A further object of the invention is to 25 provide a ladder which can be quickly converted from one form or size of ladder into any size or form.

30 A still further object of the invention is to provide a practical and easily actuated locking means for retaining the extension sections of the ladder in their adjusted positions.

35 With the above and other objects in view, the invention consists in the novel features of construction, arrangement and combination of parts hereinafter more fully described and finally pointed out in the claims hereto appended.

Referring to the accompanying drawings forming a part of this specification wherein like characters of reference denote similar parts throughout the several views:

40 Figure 1, is a side view of our improved ladder with the extensions closed.

Fig. 2, is a front elevation of the ladder looking in direction of arrow 2 of Fig. 1.

Fig. 3, is a side elevation of the ladder in 45 a collapsed or closed position.

Fig. 4, is a longitudinal sectional view of the ladder in its collapsed or folded position.

Fig. 5, is a rear elevation of the front 50 ladder section, looking in direction of the arrow 5 of Fig. 3.

Fig. 6, is a front elevation of the rear ladder section, looking in direction of the arrow 6 of Fig. 3.

55 Fig. 7, is a side elevation of the ladder

with the front section extended to rest upon a lower level than the back ladder section.

Fig. 8, is a front elevation of the front ladder section showing the extension member of the ladder extended to one of its 60 several extended positions.

In carrying out the aim of our present invention, we employ two ladder sections, a front ladder section A, and a rear ladder section B, the front ladder section carrying 65 an extension ladder section C and the rear ladder section carrying an extension ladder section D. The extension ladder section C has telescopic or sliding engagement with the front ladder section A, while the ex- 70 tension ladder section D has telescopic or sliding engagement with the rear ladder section B.

The front ladder section A, comprises two side rails or legs 1 suitably spaced apart and 75 united by means of the cross-pieces 2 spaced along the front faces of the side rails 1 and the cross-pieces 3 spaced along the rear faces of the side rails 1. The upper ends of the side rails 1 are positioned closer together 80 than the lower ends of side rails 1, so as to provide a tapered front ladder section A. The inner face of each side rail 1, is provided with a wedge shaped member 4 extending downwardly a suitable distance 85 from the top of each side rail 1, to provide the two parallel side guide walls 5.

The extension ladder section C is slidably mounted between the side rails 1 and their uniting cross-pieces 2 and 3, as clearly shown 90 in Figs. 2 and 4. The extension ladder section C consists of the two parallel side rails 6, which rails are united in spaced relation by means of the suitably spaced foot boards or steps 7, as clearly shown in Figs. 4 and 5. 95 The upper face of each cross-piece 2 is beveled, as at 8, to lie in a plane with the top face of the steps or foot-boards 7, as clearly shown in Fig. 4.

The locking means for holding the extension ladder section C, in its normal as 100 well as any of its extended positions, consists of a lever 9 pivoted, as at 10 to one of the rear cross-pieces 3, as clearly shown in Fig. 5. A pair of locking rods 11 are connected at their one end to the head of the lever 9, on opposite sides of the pivot 10. The rods extend outwardly therefrom, pass through the bearings or guides 12, are then bent at a right angle to provide the arms 110

13 which in turn are finally bent at a right angle at their free ends to provide the locking ends 14 which pass through opposed and aligned opening 15 in the side rails 1, of ladder section A and wedge plates 4 and the registering openings 16 in side rails 6 of the extension ladder section C. The side rails 6 of the extension ladder section C are provided with a plurality of suitably spaced 10 sets of lock receiving openings 16, as clearly shown in Fig. 5, so that the extension ladder section C may be adjusted or extended to various elevations and securely locked in the adjusted or extended position, as is manifest.

The rear ladder section B comprises two side rails or legs 17 suitably spaced apart and united by means of cross-pieces 18 spaced along the front faces of the side rails 20 17, and the cross-pieces 19 spaced along the rear faces of the side rails 17. The upper ends of the side rails 17, like side rails 1, are positioned closer together than the lower ends of the side rails 17, so as to provide a tapered rear ladder section 25 B. The inner face of each side rail 17, is provided with a wedge shaped member 20 extending downwardly a suitable distance from the top of each side rail 17, to provide 30 the two parallel side guide walls 21.

The extension ladder section D for the rear ladder section B is slidably mounted between the side rails 17 and their uniting cross-pieces 18 and 19, as clearly shown in 35 Figs. 4 and 6. The extension ladder section D consists of the two parallel side rails 22, which rails are united in suitable spaced relation by means of the cross-pieces 23 interposed between the rails 17, as clearly shown 40 in Fig. 4.

The locking means for holding the extension ladder section D, in its normal, as well as any of its extended positions, consists of a lever 24, pivoted as at 25 to one of the 45 front cross-pieces 18 of the rear ladder section C, as clearly shown in Fig. 6. A pair of locking-rods 26 are connected to the head of the lever 24, on opposite sides of the pivot 25. The rods 26 extend outwardly from the head of lever 24, pass through suitable bearings or guides 27, are then bent at a right angle to provide the arms 28 which in turn are finally bent inwardly at a right angle at their free ends to provide the locking 55 ends 29, which ends 29 pass through opposed and aligned openings 30 in the side rails 17 of the rear ladder section B and the wedge plates 20 thereof and the registering openings 31 in the side rails 22 of the extension 60 ladder section D. The side rails 22 of the extension ladder section D are provided with a plurality of suitably spaced sets of the lock receiving openings 31, as clearly shown in Fig. 4, so that the extension ladder 65 section D may be adjusted or extended to

various elevations and securely locked in the adjusted or extended position, as is manifest.

The levers 9 and 24 are each held in their normally closed position by means of the 70 coiled springs 32 and 33, respectively.

The upper end of each of the side rails 22 of the extension ladder section D is provided with a pair of suitable ears 34 which are fixed at one end thereto. The ears 34 75 each extend a suitable distance beyond the front face of the side rails 22 and are each provided with an opening 35, which opening 35 is adapted to register with openings 36 in the side rails 6 of the extension ladder 80 section C to receive a suitable hinge-pin 37 having a suitable hand-grip 38 formed at one end thereof, as clearly shown in Fig. 2, of the drawings.

The operation of the ladder is as follows: 85

When it is desired to move the ladder extension C from one position to another, to either lengthen or shorten the front ladder section A, the operator merely pulls lever 9 away from the spring 32 which causes the withdrawal of the locking arms 14 from the 90 opening 16 thereby permitting the ladder extension section C to be freely moved endwise in either direction. After this operation the two sections A and C are again 95 locked, as is manifest, to hold the extension C from movement in either direction.

When it is desired to either lengthen or shorten the rear ladder section B, the lever 24 is manipulated the same as lever 9, thereby withdrawing the locking arms 29 from the openings 31 of the extension section D to permit free movement in either direction of the extension D with relation to the rear ladder section B, as is manifest. 100

From the foregoing description, it will be readily understood that the ladder sections A and B may be readily adjusted to various lengths, so as to provide a ladder which may be set to meet various requirements expected of ladders. The ladder can be used in many different ways, as is manifest. It can be used as a double ladder, or by removing the pin 37, as two independent ladders of the extension type, and by removing either 110 extension from its holder or supporting section, several single ladders can be provided, if desired.

The many advantages and uses of a ladder as herein described, will readily suggest 115 themselves to those skilled in the art to which it appertains, hence a lengthy statement of the many advantages and uses to which the ladder may be put is thought unnecessary.

We do not desire to be understood as limiting ourselves to the details of construction and arrangement as herein described and illustrated, as it is manifest that variations and modifications may be made in the 120 125 130

features of construction and arrangement in the adaptation of the device to various conditions of use without departing from the spirit and scope of our invention and the 5 terms of the following claims, hence we wish it to be understood that we reserve the right to make any such changes or modifications as may fairly fall within the scope of the appended claims when fairly construed.

10 What we claim is:

1. A ladder of the class described comprising a ladder holder section consisting of a pair of side rails united by means of front and rear cross-pieces, said ladder holder section being wider at its lower end than at its upper end, a wedge plate fixed to the inner face of each side rail of the ladder holder section to provide two opposed parallel guide faces, an extension ladder section 15 comprising side rails and connecting steps slidably mounted between the two parallel guide faces of the side rails and the uniting cross-pieces of the ladder holder section, locking arms passing transversely through 20 the side rails of the ladder holder section and the wedge plates fixed thereto and entering openings in the side rails of the extension ladder section to lock the two ladder sections together and hold the extension ladder section in adjusted positions with relation 25 to the ladder holder section, a manually actuated lever pivotally connected to one of the rear cross-pieces of the ladder holder section, connections uniting the locking arms above and below the fulcrum of 30 said lever for imparting movement to the locking arms when the lever is moved in either direction and a spring for normally holding the locking arms in their innermost 35 positions.
2. A ladder of the class described, comprising a front ladder section consisting of a pair of side rails united by means of front cross-pieces and rear cross-pieces, said ladder section being wider at the bottom than 40 at the top, a wedge shaped plate fixed to the

inner face of each side rail near the top thereof to provide two parallel guide faces, an extension ladder section comprising side rails and steps slidably mounted between 50 the two parallel guide faces of the side rails and the uniting cross-pieces, locking arms adapted to pass through the side rails and wedge shaped plates of the front ladder section and enter openings arranged in the 55 side rails of the extension ladder section to lock the latter at any desired elevation with relation to the front ladder section, means for withdrawing the locking arms from the openings in the side rails of the front ladder extension to permit movement thereof; a rear ladder section consisting of a pair of side rails united by means of front and rear cross-pieces, said rear ladder section being wider at the bottom than at the top, a wedge 60 shaped plate fixed to the inner face of each side rail of the rear ladder section near the top thereof to provide two parallel guide faces, an extension ladder section comprising 65 suitably united side rails slidably mounted between the two parallel guide faces of the side rails of the rear ladder section, and the uniting cross-pieces, locking arms adapted to pass through the side rails and wedge shaped plates of the rear ladder 70 section and enter openings arranged in the side rails of the rear extension ladder section to lock the extension ladder section at any desired elevation with relation to the rear ladder section, means for withdrawing 75 the locking arms from the openings in the side rails of the rear ladder extension to permit movement thereof, and means for hingedly uniting the upper ends of the front and rear ladder extensions to permit the 80 front and rear ladder sections to be spread as desired.

In testimony whereof, we have hereunto signed the specification.

JOHN F. SOLTER.
WILLIAM GINDLER.
